UNITED STATES PATENT OFFICE.

ADOLPH EUGENE GRAU, OF NEW ORLEANS, LOUISIANA.

DREDGE BUCKET.

Application filed November 17, 1923. Serial No. 675,402.

To all whom it may concern:

Be it known that I, ADOLPH EUGENE GRAU, a citizen of the United States, and a resident of New Orleans, in the parish of Orleans and State of Louisiana, have invented certain new and useful Improvements in Dredge Buckets, of which the following is a specification.

My invention relates generally to dredge buckets, more particularly to dredge buckets of that type of construction which comprise sections which are opened and closed during the operation of the bucket, and it consists in the combinations, constructions and arrangements herein described and claimed.

An object of the invention is to provide in a dredge bucket construction of the character described means operable by fluid pressure to effect at a single operation the opening of the bucket, the ejection of the contents of the bucket therefrom and the cleaning of the inner walls of the bucket.

A further object of the invention is to provide in a dredge bucket construction means operable under the influence of fluid pressure to drive the bucket into the ground.

A still further object of the invention is to provide in a dredge bucket construction means operable by fluid pressure to hold the bucket open when the latter is empty and adapted to be moved to a position to permit closing of the bucket by the material entering the bucket during the digging stroke of the latter, whereby premature closing of the bucket before the latter has been filled to capacity is precluded.

Other objects and advantages will be apparent from the following description, considered in conjunction with the accompanying drawings, in which,

Figure 1 is a vertical section through a dredge bucket construction embodying the invention, showing the bucket in open position.

Figure 2 is a view similar to Figure 1 showing the bucket in closed position.

Figure 3 is a relatively enlarged fragmentary vertical section through a portion of the structure which is exhibited in the preceding views.

Figure 4 is a relatively enlarged transverse section along the line 4-4 of Figure 1.

Figure 5 is a side elevation of the bucket in closed position.

Figure 6 is a relatively enlarged plan view of an ejector head which is comprised in the device.

Figure 7 is a side elevation of the ejector head.

Figure 8 is a plan view of the upper cross head of a frame which is comprised in the device, and

Figure 9 is a side elevation of the bucket in open position.

Referring now to the drawings and particularly to Figures 1, 2, 4, 5 and 9 thereof, the numeral 1 designates a dredge bucket generally. This bucket is substantially rectangular in cross sectional contour at its upper end, as best seen in Fig. 4, and comprises two complementary sections or leaves 2 and 3 respectively which are hinged together at 4 at their upper ends, and which are continuously urged to a closed position, that is, the position in which the side members of one of the sections are in edge to edge abutting relation to the side members of the other section as shown in Figures 2 and 5, by spring members 6.

The specific bucket shown in the drawings is one which is adapted for use in digging close to a pile and therefore the section 3 has the end wall thereof formed to include a re-entrant portion 7 which is curved arcuately in cross sectional contour. The bucket in itself forms no part of the invention and therefore may vary considerably in construction from the form which is shown without departing from the spirit and scope of the invention as will presently appear.

The bucket 1 is suspended from a frame 8 through the agency of a plurality of arms 9. The frame 8 comprises an upper head 10, a lower head 11 and a plurality of spaced apart vertically disposed stay rods 12 which are attached at their upper ends to the upper head 10 and at their lower ends to the lower head 11 at points adjacent to the outer edges of both of these heads. With this arrangement, the heads 10 and 11 are stayed to each other and securely held in spaced parallel relation.

The head 11 is provided with pairs of adjacent spaced apart ears or lugs 13 corresponding in number to the number of arms 9, each of the arms 9 being pivotally attached at its upper end to one pair of lugs. Each of the arms 9 also is pivotally attached at its lower end, as at 14 to a pair of upstanding

ears 15 which are formed integrally with a corner portion of the bucket 1 at the upper end of the latter, there being four of the arms 9 and each connecting the lower cross head 11 with one corner portion of the bucket 1, whereby the bucket will be supported by the frame 8 with the longitudinal axis thereof in alinement with the longitudinal axis of the frame and at the same time, the sections or leaves of the bucket will be permitted to swing about the axis of the hinge connection between such sections from open position, as shown in Figures 1 and 9, to closed position as shown in Figures 2 and 5.

It, of course, is desirable that the sections of the bucket shall be held in open position at the beginning of the digging stroke. I therefore provide means operable at a single 20 operation to eject the contents of the bucket therefrom and to both clean the inner walls of the bucket and spread the sections of the bucket to closed position. Such means comprises an ejector head 16 which conforms in 25 contour to the inner wall of the upper end portion of the bucket and which is provided with rollers 17 supported on the ejector head to extend slightly beyond the peripheral edge of the latter for rolling contact 30 with the inner walls of the end portions of the bucket. It will be obvious that when the ejector head 16 has been moved bodily downward in the bucket and at the same time is maintained in horizontal position, 35 the sections of the bucket will be spread apart by the ejector head and the contact of the edges of the latter with the inner walls of the bucket will occasion the scraping or cleaning of the latter. The ejector 40 head 16 preferably is enlarged in thickness toward its center by successive steps as indicated at 18, 19 and 20 so that the central portion thereof is relatively thick. This central portion is provided with a central 45 bore or socket at 21 in which is secured the lower end of a piston stem 22, the connection being effected in any suitable manner, as through the use of a securing screw 23.

The piston stem 22 extends slidably 50 through a central opening at 24 in the lower cross head 11 and is integral at its upper end with a head 25 which is mounted for reciprocation within a vertical cylinder 26 and which constitutes a plunger or piston 55 for the latter. The cylinder 26 is supported at its lower end in a central socket or counter-bore 27 which opens through the upper face of the lower head 11. The cylinder 26, preferably, is held against movement relative to the head 11 as by having a friction-tight fit at its lower ends with the walls of the socket 27 and is closed at 60 its upper end by a head 28 which extends beyond the periphery of the cylinder into contact with the inner walls of a vertically

reciprocable hammer cylinder 29. The latter is provided at its lower end with a relatively thick head 30 having an opening 31 slidably receiving the cylinder 26. With this arrangement, the cylinder 26 is disposed in concentric relation to the vertically movable hammer cylinder 29 and the head 28 of the cylinder 26 constitutes a piston for the cylinder 29. The latter is provided with pairs of outwardly extending lugs 32 which 70 embrace the stay rods 12 and hold the cylinder 29 against movement laterally of the frame 8 while permitting free vertical movement of the cylinder 29 between the heads 11 and 12, the stay rods 12 serving as guides 75 for the cylinder 29. The latter is closed at its upper end by a head 33 which is provided with a threaded opening 34 engaged by an end portion of a supply conduit 35 which may be connected with any suitable 80 source of pressure fluid supply. The conduit 35 includes a flexible portion 36, permitting bodily movement of the hammer cylinder without injury to the conduit.

The piston stem 22 is provided with an 85 axial passage 37 which opens at its upper end through the piston 25 and communicates at its lower end with a radial bore or passage 38 which is threaded for engagement with an end portion of a conduit 39. The axial passage 37 therefore does not extend the entire length of the piston stem 22, but terminates at its lower end in a portion 90 of the piston stem which is incapable of movement up to the level of the head 11. The conduit 39 also includes a flexible portion 40 permitting movement of the conduit as a unit with the piston stem 22 and the conduit 39 may be connected with any suitable 95 source of pressure fluid supply.

From the foregoing description of the various parts of the device the operation thereof may be readily understood. A hoisting cable 41 for supporting the bucket and the frame 8 as a unit may be attached 100 to the frame 8 through the agency of an eye-bolt 42 which is upstanding from the central portion of the upper head 10. Assuming that the bucket has been filled, the 105 operation is as follows: Pressure fluid is admitted to the cylinder 26 above the piston 25 through the conduit 39 and the axial passage 37. The piston 25 is forced downward, thereby pushing the ejector head 16, which has been located in the upper part of the bucket, downward in the bucket with the edge portions of the ejector plate in sliding contact with the inner walls of the bucket sections which will be thoroughly cleaned 115 because of the scraping contact of the ejector head therewith. The bucket and the frame 8 then are lowered as a unit until the lower or cutting edges of the sections of the bucket are in contact or rest upon the material in which the excavation is to be made. 120

Pressure fluid is admitted through the conduit 35 to the space within the hammer cylinder 29 above the piston 28. The hammer cylinder 29 being freely movable in sliding engagement with the rods 12, the cylinder 26 will be moved vertically until in elevated position and until stopped by the upper head 10. It is to be understood that the conduit 35 is provided with any suitable known means such as the two-way valve 35' located at any desirable place therealong, for controlling the flow of pressure fluid therethrough into the cylinder 29 so that pressure fluid may be alternately supplied to the cylinder 29 and permitted to escape therefrom through the conduit 35. The hammer cylinder 29 being relatively heavy will fall by gravity from its elevated position upon the lower head 11 and the impact 20 of the blow delivered thereby will be transmitted through the arms 9 to the bucket sections 10 and will cause penetration of the latter into the material which is to be removed. Successive blows of the hammer 25 cylinder will cause the bucket to penetrate or dig to a greater depth into the material and the material entering the bucket will at the same time push the ejector head upward in the bucket, thereby permitting the 30 springs 6 to function to close the bucket when it has been filled.

The conduit 39 also is provided with a two-way valve such as that indicated at 39' which can be manipulated to permit escape 35 of pressure from the cylinder 26.

Obviously, my invention is susceptible of embodiment in forms other than that illustrated in the accompanying drawings and I therefore consider as my own all modifications 40 and adaptations of the form of the device herein described and illustrated which fairly fall within the scope of the appended claims.

What I claim is:

1. In a dredge bucket construction, a bucket comprising cooperative hinged sections spring-pressed toward closed position, and an ejector head interfitting the bucket and movable from a position to permit closing of the bucket to position to eject the contents of the bucket therefrom and to spread the bucket sections apart.

2. In a dredge bucket construction, a bucket comprising cooperative hinged sections spring-pressed toward closed position, an ejector head interfitting the bucket and movable in scraping contact with the inner walls of the latter from position to permit closing of the bucket to position to effect ejection of the contents of the bucket therefrom and opening of the bucket, and means whereby the ejector head may be operated.

3. In a dredge bucket construction, a bucket comprising cooperative hinged sections spring-pressed toward closed position,

an ejector head interfitting the bucket and movable in scraping contact with the inner walls of the latter from position to permit closing of the bucket to position to effect ejection of the contents of the bucket therefrom and opening of the bucket, and pressure fluid controlled means for moving the ejector head in the bucket from the first named position to the second named position.

4. In a dredge bucket construction, a bucket comprising a pair of cooperative hinged-together sections spring-pressed toward closed position, a frame from which the bucket is suspended, an ejector head slidably interfitting a bucket and adapted when in position in the lower part of the latter to hold the sections of the bucket in open position, and means carried by the frame for moving the ejector head downward in the bucket.

5. In a dredge bucket construction, a bucket comprising a pair of cooperative hinged-together sections spring-pressed toward closed position, a frame from which the bucket is suspended, an ejector head slidably interfitting the bucket at its upper end and movable downward in the bucket in scraping contact with the inner walls of the latter, said ejector head being of such area as will occasion the opening of the bucket when the ejector head is in the lower part of the bucket, a cylinder carried by said frame and being closed at its upper ends, a piston reciprocable in the cylinder and having a depending stem portion connected at its lower end to said ejector head for operating the latter, said piston stem having a passage opening at its upper end through said piston and opening at its lower end through a side wall of the piston stem, and a conduit attached to the piston stem in communication with the lower end of the passage in the latter for supplying pressure fluid to said cylinder to cause downward movement of the piston stem, as and for the purpose described.

6. In a dredge bucket construction, a bucket comprising a pair of cooperative sections hinged together and spring-pressed toward closed position, a supporting frame comprising an upper cross head, a lower cross head and vertical stay rods connecting the edge portions of said upper and lower cross heads, arms connecting the bucket at its upper end with said lower cross head, said lower cross head having a central opening, and a counter-bore opening through the upper face thereof, a piston rod extending slidably through the central opening of the lower end, an ejector head slidably interfitting the bucket at its upper end and supported by said piston rod, a piston at the upper end of the piston rod, a cylinder secured at its lower end in the counter bore,

a head closing said cylinder at its upper end and extending beyond the periphery of the latter, a hammer cylinder closed at its upper end and mounted to slide vertically in encircling relation to said first cylinder and in sliding engagement with said stay rods, the head at the upper end of said first cylinder providing a piston for said hammer cylinder, means whereby pressure fluid may be alternately supplied to and permitted to escape from the space within said hammer cylinder above the upper head of the first cylinder, and means whereby pressure fluid may be supplied at will to the space within said first cylinder above the piston in the latter.

7. In a dredge bucket construction, a bucket comprising a pair of cooperative hinged together sections spring-pressed to a closed position, a rigid frame having a 20 cross head at its lower end, arms connecting said cross head with the corner portions of said bucket at the upper ends of the latter, a hammer cylinder supported by said frame and movable vertically in the latter 25 from a position in which it is disposed upon said cross head, and means whereby pressure fluid may be employed to lift said hammer cylinder to position to fall by gravity upon said cross head and to thus drive said bucket 30 into material which is to be excavated.

ADOLPH EUGENE GRAU.
